UNITED STATES PATENT OFFICE.

HENRY F. KEIL, OF NEW YORK, N. Y.

DOOR-SECURER.

SPECIFICATION forming part of Letters Patent No. 363,145, dated May 17, 1887.

Application filed March 8, 1887. Serial No. 230,121. (No model.)

To all whom it may concern:

Be it known that I, HENRY F. KEIL, of the city, county, and State of New York, have invented a new and Improved Door-Fastener, 5 of which the following is a full, clear, and exact description.

My invention relates to an improved door-fastener specially adapted for use with refrigerator and ice-house doors, and has for its object to provide a device whereby a door will, under all conditions, be brought up tight to the jamb, and wherein the construction will be simple and cheap and the device readily and quickly operated.

15 The invention consists in a cam-faced block attached to a spindle passing through the door, adapted to engage a plate secured to the jamb, having a double-inclined surface.

Reference is to be had to the accompanying 20 drawings, forming part of this specification, in which similar letters of reference indicate corresponding parts in all the figures.

Figure 1 is a partial elevation of the outside 25 of a door having the device attached, and Fig. 2 is a central vertical section through the device on line xx of Fig. 1. Fig. 3 is a partial elevation of the inner side of the door and jamb with the device attached, and Fig. 4 is a horizontal section through said door and jamb above 30 the attached device.

In carrying out the object of the invention an opening or aperture is made in the door 35 a convenient distance from the outer edge and upon the outside of the door, surrounding said opening, a plate, A, is suitably attached, which plate is provided with lugs a and a' at right angles to each other, integral with the outer lower and inner end thereof, the lug a being horizontally situated above the lower edge and 40 the lug a' occupying a vertical position forward the inner edge, as shown in Fig. 1. Upon the inner side of the door, and surrounding the aforesaid opening therein, a plate, B, provided with an inwardly-projecting collar, is secured, said plate having a plain flat surface adapted to extend a distance from the 45 opening toward the inner edge of the door, as shown in dotted lines, Fig. 1, and positive lines, Fig. 2.

50 A square spindle, C, having a thread cut at one end and a handle, C', integral with the

other, is passed through the opening in the door until the shoulder c , formed by the enlarged under side of the handle, is substantially in contact with the plate A. The aperture in the plate A is made larger than the opening in the door, to receive a collar, c' , nearly of equal diameter with said plate-aperture formed upon the spindle C, intervening said plate and handle, which collar, when the spindle is passed through the opening in the door, bears slightly against the surrounding surface, as shown in Fig. 2. The handle C' is provided with a lug, d , at its lower end, integral therewith, adapted to engage the lugs a and a' upon the plate A under circumstances hereinafter set forth. A segmental block, D, is now constructed, having opposite cam-faces, d' , which block is preferably made with a deep recess, d'' , in its enlarged end, to reduce the weight thereof, and the said cam-faced block is provided with a circular projection, E, centrally its straight edge, having a square opening from end to end adapted to receive the spindle C.

The cam-block D is slid over the spindle upon the inner side of the door, the circular projection E forming a washer spacing the cam from the plate B, and a lock-nut, e , is screwed upon the end of the spindle, whereby the cam is held in rigid contact with said spindle, as illustrated in Figs. 2 and 4.

Upon the inner facing of the jamb a plate, F, is secured, having a narrow right-angular projection, F' , the outer face of which projection 85 is inclined in opposite directions from the center, the plate being so secured to the jamb as that one incline surface of the plate F will engage one face at the reduced end of the block D when said block is carried from a vertical 90 to a horizontal position, as illustrated in Fig. 4.

The block D is made with a double face and the plate F with a double-inclined surface, so that the device may be used either right or left, as found most convenient.

In operation, when the door is open, the lug d upon the handle rests upon the lug a of the face-plate A, the handle and block being in a horizontal position facing the inner edge of the door. When the handle and consequently 100 the block are carried to a vertical position, the door may be closed, and when so closed, if

the handle be carried downward in the direction of the outer edge of the door, the reduced end of the cam engages the incline face of plate F, and the farther the handle is carried down 5 the tighter the door is pressed against the jamb. The fastening is secure when made, and easily released. Ordinarily the handle need only be carried to a horizontal position to effect a tight joint; but a full quarter-turn farther may 10 be made in the event the door is badly shrunk or warped.

Having thus fully described my invention, what I claim as new, and desire to secure by Letters Patent, is—

15 1. A fastening for doors, consisting of a spindle passing through the door, having a handle secured at one end and a double cam-faced block at the other, said block adapted to en-

gage a double-inclined faced plate attached to the door-jamb, substantially as shown and described. 20

2. The combination, with a square spindle, C, having a handle, C, provided with a lug, d, integral with one end, and a double cam-faced block, D, secured at the other end by a 25 lock-nut, e, an inner plate, B, and an outer plate, A, having lugs a a', of a plate, F, having a projection, F', the face of which is inclined in opposite directions from the center, substantially as and for the purposes herein 30 set forth.

HENRY F. KEIL.
